UNITED STATES PATENT OFFICE

RALPH S. WHALEY, OF SEATTLE, WASHINGTON, ASSIGNOR TO PETROLEUM HEAT AND POWER COMPANY, OF NEW YORK, N. Y., A CORPORATION OF DELAWARE

OIL BURNER

Application filed July 9, 1930. Serial No. 466,650.

This invention relates to an improvement in oil burning apparatus and has for one of its objects the provision of a construction whereby the oil burner is adapted for use in any territory regardless of the type of electric power in that territory, means being provided whereby an electric motor of any type may be coupled to the burner to drive the same.

10 In the drawing I have shown an embodiment of my invention in plan partly in section.

Referring to the drawing in detail, 1 designates the burner housing. The burner is 15 of the mechanical type, 2 designating the mechanically driven burner shaft mounted for rotation within the housing 1.

The burner shaft is provided with a pulley 3 within the housing.

20 4 designates an L-bracket fastened to the exterior of the housing, the bracket being adjustable transversely of the burner, slots 5 permitting this adjustment.

6 designates a motor mount or stand, mounted 25 on the exterior of the burner housing. A slot and bolt connection 6' adjustably attaches the plate or stand 6 to the bracket 4 so as to permit of adjustment of the plate relatively to the bracket in the plane of movement of the plate on adjustment of the bracket but in a transverse direction. The plate is also adjustably attached to the housing through bolt 7 and slot 7' which connection permits of the aforesaid adjustment of the bracket 4 and plate 6.

30 This mount can be adjusted lengthwise as well as transversely of the burner.

8 designates an electric motor 10 bolted to the mount 6, the armature shaft 9 thereof 35 carrying a pulley 10. A driving belt 11 is carried by the pulleys 3 and 10.

This construction thereof permits of an electric motor of any desired type to be employed for driving the burner and therefore 40 permits of my improved apparatus being installed in any territory regardless of the type of electric power available.

What I claim is:—

Means for adjustably mounting a motor on 45 a machine comprising a plate for receiving

the motor, a supporting bracket for said plate, a slot and bolt connection for attaching the plate to said bracket for sliding relative adjustment, a slot and bolt connection for anchoring said bracket to said machine for sliding adjustment in a direction transverse to said first adjustment, and a slot and bolt means for adjustably anchoring another portion of said plate to said machine to provide for the aforesaid sliding adjustments of the 55 bracket and of the plate and bracket.

This specification signed this 1st day of July, 1930.

RALPH S. WHALEY.
